2,114,143

VOLTAGE REGULATOR

Thomas M. Hunter, East Orange, N. J., assignor
to American Transformer Company, Newark,
N. J.

Application December 19, 1935, Serial No. 55,191
Renewed July 10, 1937

19 Claims. (Cl. 171—119)

This invention relates to a new form of voltage regulator, although retaining all the fundamental principles and many of the parts shown and described in my Patents 2,014,570, issued September 17, 1935; and 1,993,007, issued March 5, 1935.

In the first-mentioned patent, there are described different methods by which voltage regulation has been obtained in the past, so that these need not be further described herein. In the second-mentioned patent, certain details of construction and circuit arrangements have been set forth.

The object of my present invention is to provide still further improvements in the mechanism entering into the operation of a regulator of the type described in my prior patents, and at the same time provide a new circuit arrangement for carrying my invention into practice.

Other objects will appear from the description which follows.

In the drawings accompanying this specification,

Figure 1 is an elevational view of my new type of regulator, with the casing removed.

Figure 2 is a view similar to Figure 1, but looking from right to left.

Figure 3 is a part-sectional and part-elevational view on the line 3—3 of Figure 1.

Figure 4 is a view taken on the plane 4—4 of Figure 3.

Figure 5 is a view on the line 5—5 of Figure 3.

Figure 6 is a view on the line 6—6 of Figure 3, with the mechanism in one position of operation.

Figure 7 is a view similar to Figure 6, but with the parts in a different position of operation.

Figure 8 is a view similar to Figures 6 and 7, but with the parts in a still different position in the cycle of operation.

Figure 9 is a simplified wiring diagram of the regulator circuits, minus the automatic control features.

In the various views, wherein like numbers refer to corresponding parts, 1 represents, broadly, a framework for supporting all parts of the regulator, the outside casing not being shown in Figures 1 and 2, but the upper portion of it, 2, being shown in Figure 3. The casing 2 is provided with a closure plate 3 carrying a downwardly extending compartment 4, to the bottom wall of which is fastened a stub shaft 5 carrying a disc 6 having a single tooth 7 (see Figure 5) which is adapted to engage notches 8 in a pair of Geneva gears 9 and 10. These Geneva gears are rotatably carried with shafts 11 and 12 that have

bearings in the bottom of the compartment 4 and extend upwardly within the compartment. The shaft 11 carries a switch arm 13, while the shaft 12 carries a switch arm 14. The switch arms 13 and 14 are adapted to make contact, alternately, with contact studs a to p inclusive (see Figures 4 and 9), these contacts being carried by studs 15 supported on a block 16 of suitable insulating material.

The compartment 4 has a cover 17 fastened thereto in any satisfactory manner as by lag screws 18; one of the frame bolts 19 is shown as also passing through this auxiliary cover. Mounted on the cover 17, is a limit switch and mechanical stop 20, a gear box 21, a motor 22, a condenser 23 used in connection with the motor, a worm drive gear reduction 24, bearings 25 and 26, and an operating shaft 27 which is supported by the bearings 25 and 26. Mounted on the shaft 27 is a sleeve carrying clutch 28 which may be operated by a member 29 to which is attached a lever 30. The shaft 27 carries a hand-wheel 31 whereby the shaft 27 and parts connected thereto may be operated by hand when the clutch, through the control rod 30, is operated to properly position the clutch for manual operation. It is to be understood that the control rod 30 extends outwardly so as to be readily operated, the same as the handwheel 31.

The gear box 21 contains a bevel gear 32, carried on the shaft 27, which is adapted to mesh with a cooperating gear 33 carried on a shaft 34 supported by bearings 35. On the end of the shaft 34 is an internal gear 36 adapted to engage a pinion 37 carried on a drive shaft 38 which extends downwardly through the compartment 4 and has a bearing in the bottom wall thereof. Adjacent the outer surface of the bottom wall of the compartment 4, the shaft 38 carries a pinion 39 which meshes with a gear 40 which is also carried by the stub shaft 5 adjacent the single-tooth gear 6.

The framework 1 supports a collector 41 of the commutator type, the bars of which are engaged by brushes 42 carried on a support stud 43 which in turn is carried by a disc-like member 44 preferably of strong insulating material. While I have shown three brushes 42, it is to be understood that the number of brushes depends on the amount of current to be carried and is referred to broadly in the claims as "a brush".

A stud 47, comprising part of the commutator structure, has mounted thereon a track member 49 having an extended bearing sleeve 49' whereby the member 49 may be rotated about the stud 47, being

held thereon by a washer and nut 50. The sleeve 49 supports an insulator 48 on which are mounted a disc 44 and a disc 48, and a metallic member 45 fastened to the disc 44 in any satisfactory manner. Between the insulating discs 44 and 48, a pigtail 51 is positioned, one end of it being connected to the metallic member 45, which in turn is electrically connected to the stud 43 carrying the brush 42, the other end of the pigtail or 10 flexible cable 51 being connected to another circuit element to be later referred to.

The member 49, which I refer to in the claims as a "track member", more particularly shown in Figures 6, 7 and 8, has an outer track portion 52 and an inner track portion 53 looped together at 15 adjacent points 54 and 55 to form an endless reversing track. As shown in the figures, the track is in the shape of a groove formed in the member 49. Arcuately spaced within the confines of the portions 52 and 53 of the track, are projections 56 which may be made integral with the member 49, or may be separate pins fastened thereto, but they are adapted to function like the teeth of a gear to mesh with teeth on a drive gear 57. The 20 gear 57 is carried on the end of a stub shaft 58 which in turn is supported at the free ends of a pair of spaced bars 59 and 60. The opposite ends of the bars 59 and 60 are oscillatably supported on the drive shaft 38.

30 Positioned between the bars 59 and 60, and fastened to the drive shaft 38, is a gear in the shape of a sprocket wheel 61, which is connected by a chain 62 to a second sprocket wheel 63 fastened to the stub shaft 58. Extending beyond the face 35 of the gear 57, from the shaft 58, preferably integral therewith, is a projection or pin 64 which is adapted to enter the track grooves 52 and 53, so that as the stub shaft 58 is turned by the sprocket wheel 61, chain 62 and sprocket 63, the 40 drive gear 57 will engage the projections 56 and thereby turn the member 49 in the direction of the arrow shown in Figure 6. It will be noted in this figure that the drive gear 57 is operating on the inner side of the projections 56. When the 45 last projection 56 is reached, as shown in Figure 7, the pin or projection 64, moving in the track, will pass around the loop end 55 into the position shown in Figure 8, or on the opposite sides of the projections 56. Since the drive wheel 50 57 is turning in the same direction, it will be obvious that the direction of rotation of the member 49 will be reversed, as the frame or bar members 59 and 60 will oscillate about the drive shaft 38 to allow the drive gear 57 to take up this 55 reversing position.

It is to be understood that the number of projections 56 on the track member 49, and the teeth in the drive gear, and other associated sprockets and gears, is such as to act in synchronism to move 60 the single-tooth gear 6 and the Geneva gears 9 and 10 at certain definite intervals; that is to say, when the commutator brush 42 has reached the limit of its movement in one direction around the collector 41, the Geneva gears 9 and 10 are 65 operated to move the switch levers, either 13 or 14, alternately just before the drive gear 57 moves to its reversing position as described.

The frame 1 carries a main transformer 65, a buck-and-boost transformer 66, a collector transformer 67, and a reactor 68, all of which are connected as shown diagrammatically in Figure 9, wherein it is seen that the transformer 65 has preferably the central portion, designated as the primary, to which a source of power, having any 70 suitable voltage, such, for example, as that

marked, namely 208 volts, may be applied. The transformer 65 has a plurality of coarse taps α to ρ inclusive connected alternately to the rotary switches 13 and 14, as indicated and heretofore referred to. The switch levers 13 and 14 serve to 5 interconnect the coarse taps with the collector transformer 67 which has a plurality of fine taps 69; that is to say, at one or more turns, or every turn, or, if desired, at a fraction of a turn. These fine taps 69 are connected to the bars of the collector 41, alternate taps passing through the reactor 68 as described in my Patent 1,993,007, heretofore referred to, for the purpose of eliminating 10 sparking at the brush 42 as the same moves from one commutator bar to another. 15

The collector brush 42 is connected to one end of the primary winding P of the buck-and-boost transformer 66, while the other end of the primary is connected at the central point 70 of the transformer 65. The secondary S of the transformer 20 66 has one end connected to the source of power, the voltage of which is to be regulated, while the other end is connected to the primary of a load circuit illustrated in the form of a testing transformer 71, the load being applied to the secondary 25 thereof.

From what has been said, it will be seen that the operation of the regulator will be understood, as it is similar to that shown and described in my second-mentioned patent referred to in the 30 early part of the specification, except for this general difference: That when the switches 13 and 14 pass to one side of the central tap 70, the action on the primary P of the transformer 66 is reversed from the action when the switches are 35 connected to taps on the opposite side of the central tap 70. When the switches 13 and 14 are on the taps h and i , and the brush is at the center of its travel around the commutator, zero voltage is applied to the winding P of the transformer 66, 40 so that the range of regulation is from zero to double the voltage of the source of power. In the case illustrated, this regulation is from zero to 416 volts in very smooth, gradual steps.

As heretofore referred to, the regulator may be 45 operated manually by the handwheel 31, or automatically by the motor 22. The automatic devices are generally referred to and claimed in my Patent 1,993,007, so they are not shown in the present diagrammatic arrangement, nor described 50 in detail herein.

What I claim is:

1. A voltage regulator including the following instrumentalities; at least a pair of separate transformer windings, one having coarse taps 55 and the other fine taps, the coarse taps from one winding being interconnected to the other winding through a pair of independently operable direct-contact-making switches with means for operating the switches alternately so the circuit between the windings, including the load circuit, is never opened, a collector of the commutator type having bars connected to the fine taps of said other winding, a brush adapted to be continuously connected to a circuit whose 60 voltage is to be regulated, said brush being mounted for clock and anti-clockwise rotation around said collector, and means for moving said brush at synchronous intervals between movements of said switches; further characterized in 65 that said motions of the brush around the collector are controlled by a device including a rotatable member connected to said brush mounting to rotate the same, said rotatable member having radially spaced arcuately formed 70

tracks meeting to form an endless reverse loop, with a plurality of gear-engageable parts arcuately spaced between the parts of the track, a gear-wheel adapted to have its teeth engage said engageable parts to rotate said member, means for rotating said gear wheel and means associated with said gear wheel cooperating with said track to cause said gear wheel to move around the last of said engageable parts at the reversible 10 part of the loop, thereby reversing the direction of rotation of said member.

2. A voltage regulator as set forth in claim 1, further characterized in that said track comprises a re-entrant groove in one face of said 15 rotatable member, and said engageable parts are in the form of projecting pin-like parts adapted to mesh with the teeth on said gear, and said associated means comprises a stud-like formation extending beyond the face of said gear into 20 said groove.

3. A voltage regulator as set forth in claim 1, further characterized in that the rotating means for said gear wheel comprises a pair of interconnected chain sprocket wheels, one of 25 which is fixed on a drive shaft, while the other is carried on a stub shaft supported between two bars pivotally mounted on said drive shaft, said stub shaft also carrying said gear wheel and terminating in a formation for cooperation with 30 said track.

4. A voltage regulator as set forth in claim 1, further characterized in that said track comprises a re-entrant groove in said rotatable member and said engageable parts are projecting 35 members adapted to mesh with said gear; further characterized in that the rotating means for said gear wheel comprises a pair of interconnected operating members, one of which is fixed on a drive shaft, while the other is carried on a stub 40 shaft supported between spaced bars pivotally mounted on said drive shaft, said stub shaft also carrying said gear wheel, and means extending beyond the face of said gear wheel into said groove for the purpose described.

5. A voltage regulator as set forth in claim 1, further characterized in that said brush mounting includes a pair of spaced discs preferably of strong insulating material, said discs being arranged to rotate with said member carrying 50 said track, a stud carried by said disc nearest the collector, the brush being carried by said stud, and a flexible cable carried between said disc and having one end connected to said stud to complete an electrical connection to said brush 55 as said discs and brush are rotated.

6. A voltage regulator including a casing carrying therewithin at least a pair of separate transformer windings, one having coarse taps and the other fine taps, a closure plate for the 60 casing, a pair of independently operable rotatable switches carried on the closure plate within the casing and serving to connect said coarse taps to the other winding, a collector of the commutator type mounted within the casing below 65 said switches and having the bars thereof connected to the fine taps of said other winding, cooperating means for the regulator carried on the exterior of the closure plate and including a drive shaft extending from the plate toward the 70 collector, a pinion on said shaft, a gear rotatably mounted on a part of said plate and adapted to be operated by said pinion, a single-tooth disc operated by said gear and a pair of Geneva gears mounted for rotation at opposite ends of a diameter of said gear, a stub shaft positioned on

the axial line of said collector and carrying thereon a plurality of rotatable members, a brush, adapted to be continuously connected to a circuit, the voltage of which is to be regulated, carried by one of said members in operative engagement with the collector bars, an endless direction-reversing track carried by another of said members, driving means on said track member arcuately spaced within the confines of the track, means including a drive gear coaxing between said drive shaft and the driving means on said track member for rotating the same, and means associated with said drive gear and shaft for cooperating with the track for reversing the direction of action of the drive gear on said track member driving means, the various gears and interconnected parts being constructed and arranged so the said brush is moved at synchronous intervals between alternate movements of said Geneva gears.

7. A voltage regulator as set forth in claim 6, further characterized in that the closure plate for the casing carries a compartment within which said pair of switches are mounted.

8. A voltage regulator as set forth in claim 6, further characterized in that the closure plate for the casing carries a compartment within which said pair of switches are mounted, said compartment opening through the closure plate and having a cover for said opening, while said regulator-operating means is mounted on said cover with the said drive shaft extending through said switch compartment, and having a bearing in a wall thereof, while the pinion driven gear and Geneva gears are also mounted for rotation on a wall of the compartment.

9. A voltage regulator as set forth in claim 6, further characterized in that the closure plate for the casing carries a compartment within which said pair of switches are mounted, said compartment opening through the closure plate and having a cover for said opening, while said regulator-operating means is mounted on said cover with the said drive shaft extending through said switch compartment, and having a bearing in a wall thereof, while the pinion driven gear and Geneva gears are also mounted for rotation on a wall of the compartment, and further characterized in that the operative connection between the said drive shaft and the track member includes; a pair of spaced bars oscillatably mounted on the inner end of said shaft adjacent said pinion, a pair of sprocket wheels having interconnected operating means and positioned between said bars, one wheel being fast on said drive shaft, while the other is fixedly carried on a stub shaft rotatably supported at the free end of said bars, said drive gear for operating said track member being on the end of said stub shaft.

10. A voltage regulator as set forth in claim 6, further characterized in that the operating means on the closure plate may be either manual or automatic, with means for shifting from one to the other.

11. A voltage regulator including the following 65 instrumentalities; at least a pair of separate transformer windings, one having coarse taps and the other fine taps, the coarse taps from one winding being interconnected to the other winding through a pair of independently operable direct-contact-making switches with means for operating the switches alternately so the circuit between the windings, including the load circuit, is never opened, a collector of the commutator type having bars connected to the fine taps of 70 75

- 5 said other winding, a brush adapted to be continuously connected to a circuit whose voltage is to be regulated, said brush being mounted for clock and anti-clockwise rotation around said collector, and means for moving said brush at synchronous intervals between movement of said switches; further characterized in that special means are provided for reversing the direction of rotation of said brush about the collector 10 after it has reached its full travel in one direction, said means including a member mounted for simultaneous rotation with the brush, said member having arcuately arranged radially spaced portions joined at spaced points into an endless track, with arcuately spaced projecting parts within the confines of the track, a driving gear wheel adapted to engage said projecting parts to turn said member, and means engaging said track to cause said gear wheel to move from one 15 side of said projecting parts to the other side thereof, thereby automatically reversing the direction of rotation of the track member when the brush has reached its full travel in one direction.
- 20 12. A voltage regulator including the following instrumentalities; at least a pair of separate transformer windings, one having coarse taps and the other fine taps, the coarse taps from one winding being interconnected to the other winding through a pair of independently operable direct-contact-making switches with means for operating the switches alternately so the circuit between the windings, including the load circuit, is never opened, a collector of the commutator 25 type having bars connected to the fine taps of said other winding, a brush adapted to be continuously connected to a circuit whose voltage is to be regulated, said brush being mounted for clock and anti-clockwise rotation around said collector, and means for moving said brush at synchronous intervals between movement of said switches; further characterized in that special means are provided for reversing the direction of rotation of said brush about the collector after 30 it has reached its full travel in one direction, said means including a member mounted for simultaneous rotation with the brush, said member having arcuately arranged radially spaced portions joined at spaced points into an endless track, with arcuately spaced projecting parts within the confines of the track, a driving gear wheel adapted to engage said projecting parts to turn said member, and means engaging said track to cause said gear wheel to move from one 35 side of said projecting parts to the other side thereof, thereby automatically reversing the direction of rotation of the track member when the brush has reached its full travel in one direction, and further characterized in that the track 40 is in the form of a groove within which said engaging means moves, said driving gear wheel being mounted on a driving mechanism that can oscillate about a driving center, whereby said driving gear can follow the directions imposed by 45 the track.
- 50 13. A brush-reversing mechanism for a voltage regulator of the kind herein described including, a drive shaft, a member for operating the brush, said member having arcuately arranged radially spaced portions joined in series to form an endless loop reversing track, arcuately spaced projections within the confines of the track, a gear wheel for engaging said projections, said gear wheel being carried on a mounting which is oscillatably positioned on said drive shaft, means 55
- 70 75

for turning said gear wheel from said drive shaft, and means cooperating between said track and mounting to cause said gear wheel to move so as to engage said spaced projections on opposite sides thereof when the loop ends of the track are reached by said means. 5

14. A brush-reversing mechanism for a voltage regulator as set forth in claim 13, further characterized in that said gear wheel mounting comprises, two spaced bars oscillatably supported on the drive shaft, a pair of sprocket wheels with a chain interconnecting them, one wheel being fast on the shaft between said bars, the other fast on a stub shaft carried at the free ends of said bars, the gear wheel being mounted on the 10 end of the stub shaft which has a projection comprising said cooperating means, while the said track is in the form of a groove within which said cooperating projection moves. 15

15. In a voltage regulator of the type herein 20 described wherein a collector of the commutator type has its bars connected to the fine taps of a transformer winding and a pair of rotary switches have their alternate contacts connected to coarse taps on another transformer winding, the rotating arms of said switches being connected to the first-mentioned winding and the collector is provided with a brush mounted for rotation around the collector, said brush being connected continuously in a circuit whose voltage is to be 25 regulated; further characterized in that said switch arms and brush are operated by devices connected to a drive shaft which may be controlled manually and automatically, the brush operating devices including a disc-like member 30 having a reversing endless groove in one face thereof with gear-engageable parts arcuately spaced within the confines of the groove, and a drive gear oscillatably mounted on and indirectly driven from said drive shaft, and means moving 35 in said groove for causing the drive gear to move so as to engage said gear-engageable parts on opposite sides thereof, thereby reversing the direction of rotation of said disc-like member, the reversal being synchronized with the movement 40 of said switch arms as and for the purpose described. 45

16. A voltage regulator including a transformer having, in effect, a continuous winding, the central section of which comprises the primary and 50 adapted to have a source of power connected thereto, the winding having coarse taps therefrom, a second transformer having a winding with fine taps, a pair of independently operable direct contact making switches serving to interconnect the coarse taps to the second-mentioned transformer winding, means for operating the switches alternately so the circuit between said windings, including the load circuit, is never opened, a collector of the commutator type having bars connected to said fine taps, a buck-and-boost transformer having windings thereon, the end of one winding being connected to the center 55 of the winding on the first-mentioned transformer, a brush mounted to rotate around said collector and adapted to be continuously connected to the other end of said winding on the buck-and-boost transformer, another winding of which is connected to one side of an alternating current source of power, and to a load transformer winding, the opposite terminal of which is connected to said alternating current source of power. 60

17. A voltage regulator as set forth in claim 16, further characterized in that when the said 70 75

coarse tap switches move to opposite sides of said central tap, the said buck-and-boost transformer will be caused to buck or boost the voltage impressed on its primary by the source of power.

18. A voltage regulator as set forth in claim 16, further characterized in that when the said coarse tap switches move to opposite sides of said central tap, the said buck-and-boost transformer will be caused to buck or boost the voltage impressed on its primary by the source of power, further characterized in that when the said switches are connected to taps immediately ad-

jacent said central tap, and the brush is at the center of its travel around the collector, the voltage applied to the secondary of the buck-and-boost transformer is substantially zero.

19. A voltage regulator as set forth in claim 16, characterized in that the arrangement of said transformer windings, including their taps, with said switches and collector, is such that the voltage applied to said buck-and-boost transformer has a range from zero to substantially twice the primary voltage applied to said transformer. 10

THOMAS M. HUNTER.
